Charles S. Gooding

UNITED STATES PATENT OFFICE.

WILLIAM H. ASPEGREN, OF QUINCY, MASSACHUSETTS.

BUFFER.

1,223,845.

Specification of Letters Patent. Patented Apr. 24, 1917.

Application filed April 21, 1916. Serial No. 92,754.

To all whom it may concern:

Be it known that I, WILLIAM H. ASPEGREN, a citizen of the United States, residing at Quincy, in the county of Norfolk and State 5 of Massachusetts, have invented new and useful Improvements in Buffers, of which the following is a specification.

This invention relates to buffers for doors, windows or the like, the object of the invention being to provide a cheap, simple device capable of being applied preferably to the jamb of a door frame, but which can be applied equally well to the door itself for the purpose of absorbing the shock and reducing 10 the sound as the door is closed and to prevent vibration after the door has been closed and latched.

My invention is extremely simple, very effective, inconspicuous and very easy to attach.

The invention consists in certain novel features of construction and methods of application which are hereinafter fully described in the specification and particularly 25 pointed out in the claims.

Referring to the drawings:

Figure 1 is a combined front elevation and plan view of my preferred form of buffer, the same being shown upon a somewhat enlarged scale.

Fig. 2 illustrates the buffer, practically of normal size in front elevation attached to the jamb of a door frame.

Fig. 3 is a transverse section through a portion of a door and door frame, illustrating the buffer applied to the jamb of the door frame with the door closed against the buffer.

Fig. 4 illustrates the buffer in plan view as applied to a screen door, a portion of the door, together with the door frame, being shown in section.

Fig. 5 is an enlarged front elevation of the positioning member.

Fig. 6 is a view similar to Fig. 4 with the positioning locking member applied thereto.

Like numerals refer to like parts throughout the several views of the drawings.

In the drawings, 12 represents a section of a door frame or jamb and 13 a section of a door. My improved buffer 14 shown clearly in detail in Fig. 1 is capable of being attached to either the door frame or door in a number of different ways to meet varying

conditions. In Figs. 2 and 3 it is shown located in the rabbet 15 of the door frame 12 to which it is fastened by a nail 16. The buffer 14 consists of a piece of resilient material 17 such as rubber, felt or the like adapted to act as a cushion between the door 13 and the frame 12 to absorb the shock and reduce the sound as the door is closed. The piece of rubber or felt 17 is mounted upon a wire 18, preferably by first forming said wire in the shape of a staple and forcing the parallel arms 19 of said staple through said material 17. The arms are then bent to form two oppositely disposed V-shaped wings 20, after which the ends 21 of the wire are bent around an eyelet 22 having flanges 23 adapted to keep the ends 21 of the wire from spreading and to hold the eyelet 22 firmly clamped in position.

The nail 16 passes through the eyelet 22 and is driven into the frame 12. By shaping the wire 18 as hereinbefore mentioned in the form of oppositely disposed V-shaped wings 20, an adjustable, flexible support is formed capable of yielding when the buffer is attached to a door 24, as illustrated in Fig. 4, and coöperating with the cushioning material 17 to absorb the shock.

It is evident that should the buffer be attached to a very thin door it might be necessary to reduce the distance between the eyelet 22 and the cushioning material 17, therefore by bending the wire slightly to change the angle of the V-shaped wings, as illustrated in dotted lines, Fig. 1, the distance between the eyelet 22 and said cushioning material 17 may be greatly reduced, while the wire 18 will still retain its flexibility.

In Fig. 6 I have illustrated the buffer 14 applied to a door 24 which closes against a frame 25 upon which there is no groove as is often the case with screen doors. At such times I find it advisable to use a positioning or reinforcing member 26 clearly illustrated in Fig. 5 and formed of wire 27. One end 28 of the positioning member 26 is adapted to engage the parallel arms 19 of the buffer 14 adjacent to the resilient material 17, while the ends 29 of the wire are bent around and hold an eyelet 30 similar to the method by which the eyelet 22 is held.

A nail 31 attaches the locking member to the door 24. It will thus be seen that the

positioning member 26 will at all times hold the buffer 14 in its proper position upon the door 24.

The method of operation of my improved 5 buffer is as follows:

The buffer 14 is fastened preferably in the rabbet 15 of the door frame 12, Fig. 3, but it is evident that said buffer could be applied equally well to the corner A of said 10 frame or to the corner B of the door 13. The door 13 closing in the direction of the arrow a will close against the resilient material 17 in each instance, which will act as a cushion to absorb the shock and reduce 15 the sound of the door as it closes. If applied to a door as in Fig. 4, the door 24 closing in the direction of the arrow b will compress the resilient material 17 and also cause the flexible wire 18 to yield. 20 It will thus be seen that in this instance the resilient material 17 and the flexible wire 18 will coöperate to absorb the shock of the closing door. In Fig. 6 where there is no opportunity to locate the buffer in 25 the rabbet of the door frame the positioning member 26 is used in conjunction with the buffer 14 as hereinbefore described.

It will be seen that in each of the different 30 forms of my invention hereinbefore de- scribed the buffer consists of an angle mem- ber having two sides, one of which is formed of a piece of resilient material and the other side, projecting therefrom at substantially 35 right angles thereto, constitutes a means whereby the angle member, as a whole, may be fastened to either a door or door frame, and that the two sides of said angle member are adapted to simultaneously contact with the two sides of a right angled recess such 40 as the rabbet of a door frame, as illustrated in Fig. 3, and that said angle member is also adapted to be attached to a door and when so attached the two sides thereof will contact simultaneously with the edge and one 45 face of said door, as illustrated in Figs. 4 and 6.

Copies of this patent may be obtained for five cents each, by addressing the "Commissioner of Patents, Washington, D. C."

Having thus described my invention what I claim and desire by Letters Patent to secure is:

1. A buffer comprising a resilient member, means for attaching said resilient member to a door or door frame, said means extending substantially at right angles to said resilient member, and a positioning member engaging said attaching means and extending at right angles thereto, said positioning member adapted to be fastened to said door or door frame. 50

2. A buffer comprising an angle member, one side of said angle member consisting of a flat piece of resilient material, the other side of said angle member consisting of a U-shaped wire, the legs of said U-shaped wire passing through said piece of resilient material and forming V-shaped wings 65 whereby said piece of resilient material may be fastened either to a door or door frame, two sides of said angle member being adapted to simultaneously contact with the two sides of a right angled recess and also 70 to contact simultaneously with the edge and one face of a door to which it may be attached.

3. A buffer comprising a resilient shock and sound absorbing member, a U-shaped 75 wire, the legs of said U-shaped wire passing through said member, oppositely disposed V-shaped wings formed by said legs, an eyelet at the extremities of said legs, means passing through said eyelet adapted to 80 fasten said buffer to a door frame or door, and a positioning member adapted to engage said buffer and coöperate with said fastening device to attach said buffer to said door frame or door. 85

In testimony whereof I have hereunto set my hand in presence of two subscribing witnesses.

WILLIAM H. ASPEGREN.
